Attorney, Agent, or Firm—Burns, Doane, Swecker & Mathis

[57] CLAIM

The ornamental design for a counter, as shown and described.

DESCRIPTION

FIG. 1 is a perspective view of a counter, showing our new design;

FIG. 2 is a rear side elevational view thereof;

FIG. 3 is a right side elevational view thereof;

FIG. 4 is a cross-sectional view taken along the line 4—4 in FIG. 1;

FIG. 5 is a bottom plan view thereof; and,

FIG. 6 is a perspective showing the counter in an exploded condition.
